PATTERN MEANS FOR KNITTING MACHINES

Alfred L. Hutton, Jr., Lonsdale, and Isaac H. C. Green and Eugene St. Pierre, Pawtucket, R. I., assignors to Hemphill Company, Central Falls, R. I., a corporation of Massachusetts

Application May 16, 1941, Serial No. 393,694

9 Claims. (Cl. 66—50)

This case involves an invention in knitting machines of the circular independent needle type, more specifically, a mechanism for controlling pattern work in such machines as in tucking and horizontal striping. A dual purpose pattern means functions to pattern appropriate parts of a stocking or other fabric and in the following disclosure one specific embodiment of the invention is described with reference to the accompanying figures of drawings:

In the figures of drawings:

Fig. 1 is a side elevation of part of a machine to which the invention has been applied;

Fig. 2 is a similar elevation showing the drum and adjacent mechanism to a larger scale than Fig. 1;

Fig. 3 is a section showing the dual control drum, levers moved thereby and the positioning means for said levers;

Fig. 4 is a section taken through the drum itself;

Fig. 5 is a view similar to Fig. 3 but showing parts in a different position;

Fig. 6 is a fragmentary view of part of the drum and ratcheting means for moving the same;

Fig. 7 is a view similar to Fig. 6 but showing ratcheting pawls in an inoperative position;

Fig. 8 is a detail of a small fragment of the ratchet wheel showing the particular construction of teeth for retiming;

Fig. 9 is an elevational view from the side of the machine showing cams and part of the actuating means for moving the dual drum;

Fig. 10 shows the mechanism of Fig. 9 as seen from the back of the machine;

Fig. 11 is a section through the cylinder of the machine showing stitch cam and jack controlling mechanism;

Fig. 12 is an elevation of part of the back of the machine in which horizontal striping control means is illustrated, also certain of the control means for regulating movements of the drum;

Fig. 13 is a diagrammatic view in which cams, needle butt pathways and jack butt pathways are shown;

Fig. 14 is a sectional view of a detail of part of the operating linkage.

In some types of hosiery, especially children's wear, horizontal striping and tuck switch ornamentation are frequently employed. By an ingenious arrangement of parts and dual control, both of these functions are to be regulated by a single, central pattern means throughout the various parts of a stocking. In the top one

striping and tuck pattern is sometimes employed while in the leg and foot of the stocking another or different pattern may appear so that it is desirable to change from one of these patterns to the other automatically, that being something accomplished by the instant invention with a minimum of control mechanism and by a unitary device.

Heretofore these functions have been controlled by separate mechanism, for example, a chain control for the horizontal striper and drum or other control for the tucking. Naturally that involved considerable expense and complicated the machine, especially at or adjacent the upper part of the machine where the tuck control means has occupied space badly needed for other purposes. The dual control herein described is, generally speaking, simpler in that it occupies much less space than a chain control for a striper if that chain control were to have similar pattern scope, also this dual control is located low at the side of the frame and occupies space not particularly useful for any other purpose.

Referring to the figures of drawings, more specifically Fig. 1, the usual hosiery machine has a frame 1, needle cylinder 2 and so-called circular base 3. The type of machine illustrated is a circular, independent needle hosiery frame of Banner type, but it is to be understood that the invention applies to any hosiery machine or other knitting machine of similar construction. Latch needles are preferably employed and control of that type of needle to produce tuck stitches, either pile or float tuck, is well-known. If desired, spring beard needles may be used and the appropriate movements imparted to them for producing similar tuck stitches.

A main cam drum 4 rotates on cam shaft 5, one complete turn of the drum being made in the knitting of one stocking as is the common practice. On cam plate 6 is mounted the main cam block 7 having the usual front stitch cam 8, rear stitch cam 9, draw cam 10 and center cam 11, Figs. 11 and 13. Other cams shown in that figure will be described later relative to a discussion of the operation of the machine. The front stitch cam 8 is slidably mounted in the cam block 7 and may be moved in to and away from the cylinder to engage or fail to engage needle butts. The usual arrangement of needle butts is employed, that is, instep needles are provided with long butts and heel and toe needles with short butts. For controlling tucking, movement of this front stitch cam is automatically provided by the drum control hereinafter to be described.

Of course, movement of the cam out of engagement with needle butts prevents needles being raised to a clearing height except by jack or other control which will be described with reference to Fig. 13.

Now referring to Figs. 1, 2, 3, 4 and 5, the drum 12 is mounted for rotation on a short shaft 13 which is fixed in a bracket 14 extending downwardly from the frame 1. This drum 12 has attached thereto a ratchet wheel 15 which is also free to turn on the shaft 13 and, as will be described in detail, whenever ratchet wheel 15 is periodically moved, the drum will be advanced so that rows of studs or cam projections 16 will be caused to engage certain levers thereby to control the pattern functions involved. A friction or drag is employed to prevent overtravel or accidental movement of the drum and has three arms 17 in which spring loaded friction plungers 18 are carried, the said friction plungers bearing against a machined surface on the drum web with sufficient force to accomplish the desired purpose. The said friction means is screwed into the outer end of shaft 13 and is, to all intents and purposes, fast to and a part of that shaft.

The drum has five rows of drilled and tapped holes in which studs 16 are threaded, the movement and arrangement of such studs being dependent upon the pattern which it is desired to produce.

A bell crank lever having a more or less vertically disposed arm 19 and horizontally disposed arm 20 is freely pivoted to swing about the center of shaft 13 and carries on a shoulder screw 21 two pawls, an inner pawl 22 and an outer pawl 23. Springs 24 are attached at an extended end of the said pawls to maintain their tooth engaging ends in an operative position. The horizontal arm 20 connects to a link 25 which projects upwardly and connects at 26 to the outer end of a triangular shaped lever 27 pivoted to the side of the machine frame at 28. This lever has a hardened cam follower 29 engageable with cams 30 and 31 which are attached to the hub 32 of the 104 tooth gear 33. That gear is rotated one revolution for every four revolutions of the needle cylinder and thus the two cams impart a ratcheting movement to the drum every second revolution of the cylinder providing the pawls are in engagement with teeth of ratchet wheel 15. Obviously, a single cam or as many cams as desired may be used so that movements of the drum may be realized every revolution of the cylinder or at other intervals. A tension spring 34 tends to maintain the follower 29 in engagement with cams 30 or 31 or, in other words, pulls the link 25 upwardly except as action of the cams pushes it downwardly to impart a swinging movement to the lever 19 for the purpose intended.

The actual swinging movement as controlled by cams 30, 31 and the return movement under the influence of spring 34 would actually move the pawls throughout an arc sufficient to engage two teeth and thus advance the drum an angular distance of two teeth of the ratchet wheel at each movement. A hook 35 engages an adjustable stop 36 on the link 25 and prevents a return movement of greater extent than required to engage one tooth. In other words, after follower 29 drops from cam 30 or 31, spring 34 would tend to draw the pawl mechanism back to engage two teeth, but hook 35 when in engagement with stop 36 limits that movement to a single tooth. That is, the drum 12 is actually ratcheted a single

tooth at every two revolutions of the needle cylinder according to the specific example herein being used for illustration except at such times as hook 35 is disengaged from the stop. The outermost row of studs 16 are engageable with a follower 37 at the opposite end of the lever 38 pivoted at 39, the same being a two arm lever of which hook 35 forms an integral part. A spring 40 normally keeps follower 37 against drum 12 and hook 35 in a position to engage stop 36 as illustrated in Fig. 1. Whenever double moves are desired, one of the studs 16 will engage follower 37 moving hook 35 to a position in which it does not contact stop 36.

At certain times ratcheting of the drum is to be stopped entirely and at other times, it is desirable to retime the drum preparatory to starting up in another stocking or in another phase of the pattern. A second bell crank lever having a horizontally disposed arm 41 is also freely pivotable about the center of shaft 13 and a second arm extends downwardly to terminate in a sort of cam edge 42. That cam edge has two more or less flat portions, the first being adapted to contact a pin 43 on the pawl 22 and lift it away from the ratchet wheel teeth as shown in Fig. 6. That position is for purposes of retiming. The ratchet will be advanced by pawl 23 until a point is reached at which one tooth is skipped as at 44, Fig. 8. Then pawl 23 will work in the opening at which that tooth is missing until such time as pawl 22 is released to drop into engagement with teeth at the other side of the wheel or adjacent the opening 44.

Whenever it is desired to discontinue movement of the pawl entirely, the cam surface 42 is moved to the position of Fig. 7 whereupon pawl 22 is moved still farther away from the ratchet wheel and picks up a second pin 45 similar to 43, but projecting from the pawl 23. By means of that the second pawl will be moved out of engagement with any of the ratchet wheel teeth.

The horizontally disposed arm 41 connects to a link 46, Figs. 1, 2 and 12. That link connects at 47 to one end of lever 48 pivoted at 49 and having a toe 50 engageable with certain cams on cam drum 51. Those cams are disposed according to the pattern to be made and are of two different heights so that when the toe 50 is on the highest cam as it is in Fig. 1, the cam surface 42 will have no effect on either pawl and both will ratchet the drum. According to the disposal of studs 16 in the outermost row of the pattern drum, ratcheting movements may extend for either single teeth or double teeth. When toe 50 is on the lower cam, pawl 23 only will be in engagement with ratchet wheel teeth as in Fig. 6. When toe 50 is dropped to the surface of the drum, both pawls will be lifted away from the ratchet wheel, see Fig. 7. Referring to Figs. 1, 2, 3 and 5, a lever 52 is pivoted on a stud 53 and has a follower 54 engageable with a row of studs 16 on drum 12. A second lever 55 is pivoted at 56 and has a slotted end engageable with a pin 57 projecting from the end of lever 52. At the other end of lever 55 is connected an upwardly extending link 58 which controls the active and inactive positions of the front stitch cam 8.

Referring to Figs. 1 and 11, a rod or shaft 59 projects through post 60 and has at the end adjacent the front side of the machine an upwardly extending arm 61 with an angularly bent extension 62, said extension having a slot engageable with a projection 63 from the end of the stem 75 which carries and moves cam 8. As the rod 59

is swung, it will withdraw the cam 8 or allow the same to move in against the cylinder. At the other end of rod 59 is fixed a short lever 64 which connects to link 65 in turn engageable at its other end with one arm of a bell crank lever 66. The upwardly extending link 58 connects to the other end of that lever 66.

Whenever the toe 54 engages and rides up on a stud 16, the levers 52, 55, 66, 64 and 61 will be so moved as to withdraw front stitch cam 8 so that needles will not be raised by that cam to clear their latches. Thus tucking will be controlled by jack selection hereinafter to be described. The control from drum 12 just described is what may be termed a course by course control, and depending upon the number of cams 30 and 31, there will be a course by course tuck pattern produced so long as front stitch cam 8 is governed by the pattern projections on drum 12 and the jacks or other selecting means for determining said tuck pattern are in operation.

Referring to Fig. 13, needles have jacks 67 beneath them, said jacks having master butts 68, a plurality of removable selective butts 69 and a butt 70 on so-called short butt jacks and a butt 71 on so-called long butt jacks. Alternate needles have a long butt jack under them while intermediate needles have a short butt jack under them. A cam 72 is adapted to engage long butt jacks and thus will raise every other jack and its needle when in position. This cam is a clearing cam and will raise alternate jacks or any other set-up of long butt jacks to the exclusion of others so that tucking will be accomplished on needles not so raised so long as cam 8 is withdrawn. In other words, cam 72 will raise long butt jacks and their needles so that latches of those needles will be cleared. Other jacks and needles will not be raised, but with the particular cam arrangement shown, will take yarn and draw stitches accumulating that yarn until cleared by front stitch cam 8 as governed by pattern drum 12.

This cam 72, Figs. 1 and 11, is fixed at the inner end of a lever 73 pivoted at 74 and controlled to move the cam as desired by means of a connecting link 75, bell crank lever 76, link 77, Fig. 1, and a lever 78. This last mentioned lever pivots at 79 on a bracket 80 and has a toe 81 engageable with certain cams on drum 51 of an extent such that the cam 72 will be moved in to engage jack butts when tucking is being done, but will be withdrawn at other times. A spring 82 tends to keep the toe of the lever down on the drum or cams thereon. Spring 83 likewise draws the link 58 upwardly to maintain front stitch cam 8 inwardly or, in other words, to keep the toe 54 of lever 52 down on drum 12 except as raised by pattern studs 16. At certain times it is desired to prevent withdrawal of the stitch cam 8 even though drum 12 is being ratcheted. For example, in the toe, the drum may be retarded but naturally the front stitch cam should remain in active position. To accomplish this a stop sector 84 which forms one arm of a bell crank lever pivoted at 85 and having a second arm 86 may be swung from the position of Fig. 1 in which it is not active to a position for engaging beneath the stop collar 87 or a pin extending from it. Collar 87 is adjustable so that when engaged by sector 84, the rod or link 58 will be held in uppermost position. In that position the front stitch cam 8 can not be withdrawn even though the pattern drum is ratcheted and would normally tend to withdraw that cam. The arm 86 of the bell

crank lever just mentioned is connected by a link 88 to the lever 48 and whenever that lever drops from cams on drum 51 to the surface of the drum itself, sector 84 will engage the stop collar 87.

As shown in greater detail in Fig. 14, the lower end of link 58 is slidable within a ferrule 89. A collar 90 on the ferrule attaches by a spring 91 to the collar 87. Then when the stop sector 84 engages beneath collar 87 to hold link 58 in uppermost position, the levers 52 and 55 may still be actuated by studs 16 merely extending spring 91, the end of link 58 sliding in the ferrule 89. An adjustable collar 92 limits the movement of the rod or link 58 into the ferrule. The link 77 has at its lower end a similar sliding connection.

Now referring to Figs. 1, 2, 3, 5 and 12, a second lever 93 similar to the lever 52 is movable on the stud 53, but is attached to a collar or spacer 94 slidable along that stud. This lever likewise has a toe 95 and a pin 96 to engage within a slot in the end of a lever 97 which is in turn very much like the lever 55. This system of levers controls the horizontal striping mechanism through a link 98 attached at the other end of lever 97 and connected to the usual sector 99 which carries a bluffer for the pawl 105, Figs. 1 and 12.

The horizontal striping device itself is of conventional Banner construction. Describing the same briefly it consists of a shaft 100 having rotatable therewith a drum 101 provided with several rows of cams the number of which depends upon the number of yarn feeding levers to be controlled during striping. Five such rows of cams are shown here, but that is only by way of illustration. The shaft 100 turns in bearings 102 and 103 in a bracket 104 and is ratcheted by means of a pawl 105 engageable with teeth in a ratchet wheel 106. The pawl 105 is spring

40 pressed against the teeth of the wheel and is periodically moved to impart its ratcheting motion as a lever 105' is swung to and fro by certain appropriate cams (not shown) on 104 tooth gear 33.

45 The sector 99 is freely pivotable on shaft 100 and it is really an extension or buffer plate 107 which engages beneath the pawl 105 at certain times to prevent ratcheting of the stiper drum. The link 98 connecting to the sector 99 moves

50 the same or swings it about shaft 100 as studs 16 engage beneath the toe 95 of lever 93. When the lever is moved upwardly by one of these studs, the sector is moved to that position illustrated in Fig. 1 in which pawl 105 is rendered active. When resting on the drum 12, the opposite condition prevails and plate 107 will move beneath the pawl 105 and prevent ratcheting movement.

55 A brake shoe 108 at the end of arm 109 bears 60 against the side of ratchet wheel 106 under pressure exerted by a spring 110. This prevents overtravel or accidental movement of the stiper drum.

At times the stiper mechanism is to be re-timed and then, the lever 111 functions under the influence of certain cams (not shown) on the drum 51. The latch member 112 is spring pressed by spring 113 so that a notch 114 therein

70 will engage a projecting pin 115 in the arm 116 extending from sector 99. By means of this the sector and buffer plate are held in such a position that pawl 105 will rack the drum until arm 117 rotates around for a little more than 180 degrees from its position in Fig. 1 at which time 75 the beveled edge of that arm will strike against

a corresponding edge in front of notch 114 and release the pin 115. Then the sector and bluffer plate will move under the pawl until the pattern is started again. The retiming of the stiper is not new in this case and will not be described in greater detail.

Now referring to Figs. 3 and 5, the levers 52 and 93 are movable to engage different rows of pattern projections. The first row, that is, the outside row on drum 12, is for the purpose of controlling double moves. The lever 38 working on that row is not varied. The next two rows moving inwardly toward the frame are for the purpose of controlling tucking. The second row controls throughout the knitting of a first pattern as in a stocking top while the third row is brought into play after pattern is changed as in the leg and foot of a stocking. The two innermost rows govern horizontal striping, and likewise, the first of those or the fourth row on the drum controls striping in the top or first part of the pattern while the 5th row functions at change of pattern as in the leg. The construction is such that the second and fourth rows are used together and the third and fifth rows are used together.

Lever 93, as before stated, is attached to collar 94 and that collar is engaged by a downwardly projecting pin 118, Figs. 1, 2, 3 and 5, that pin being fixed at one end of a lever 119 pivoted at 120. The other end of that lever is formed with a toe or cam follower 121 which is engaged by a cam 122 at the inner side of a plate or thin pattern drum 123. Normally a spring 124 adjusted as to tension by collar 125 pushes inwardly on a sliding collar or spacer 126 to urge lever 52, collar 94 and attached lever 93 to the position of Fig. 3. In that position the levers are actuated by the third and fifth rows of pattern studs. Now when cam 122 contacts the end of lever 119, a movement is imparted to the mechanism moving it to the position of Fig. 5 against the tension of spring 124 in which position pattern rows 2 and 4 become active. The pins 57 and 96 are long enough and slide in the slots at the ends of the levers 55 and 97 so that no matter what the position of the first mentioned lever, the interconnection will always be effective. The mechanism just described functions at any time or times that it is desired to change the pattern being produced in both tuck and horizontal striping. Only one cam 122 has been illustrated since it is commonly desirable to change pattern once in the knitting of hosiery. Of course, more changes are easily effected, that being merely a matter of choice and accomplished by suitable number and arrangement of cams 122 or corresponding cams.

In Fig. 13 we have shown diagrammatically cams which engage needle and jack butts, also pathways of those butts. It is to be understood that the machine herein described is also adapted to knit an elastic top wherein elastic yarn is incorporated along with inelastic yarn in one of several ways, for example, as in United States Patent #2,131,720. Each of the needles will have a jack 67 beneath it, and as before explained, alternate needles have jacks with long butts 71. During the knitting of an elastic top tucking is to be controlled by withdrawing a cam 8, projecting cam 72 into position to engage the butts 71 so that every other needle, or needles having jacks with long butts, whatever the arrangement may be, will be elevated to clear latches. The needles intermediate those will not be raised to clear latches but will take yarn and tuck until

the stitch cam 8 is moved in so that all needles knit off. Of course, that stitch cam moves in on short butts and will raise the first long butt needles whereupon the cam is moved in to full extent to raise all needles for at least a course although knitting may continue for as many courses as desired before starting to tuck again.

In this Fig. 13 we have shown pathways of needle and jack butts during the knitting of an elastic top in which tucking is taking place. The butts 70 and 71 are leveled to a pathway 127 whereupon jacks with long butts 71 are to be selected by the topmost selecting plunger 128, that causing master butts 68 on those jacks to engage cam 129. Needles moving in pathway 130 over raise cam 131 are then controlled by jacks thus selected to rise in the pathway 132 whereupon they take the elastic yarn and are then drawn down with that elastic yarn by the elastic yarn drawing cam 133. Jacks may move downwardly to a low pathway 134 while needle butts are raised up by the central portion of a cam 135. Needles raise to a stitch taking level as their butts reach pathway 136, but that is not a clearing level. Those needles having jacks with long butts 71 are raised to a clearing level 137 since the cam 72 will lift the jacks having long butts 71 and of course the corresponding needles. Front stitch cam 8 is withdrawn at that time. Knitting or stitch drawing is controlled by rear stitch cam 9 after which the needles rise on raise cam 131 to the pathway 130. Jacks are moved down by cams 11 and 131 to their lowermost position.

What is illustrated in the figure shows how elastic yarn is taken on spaced needles and how tucking may be controlled through jacks and cam 72 so long as front stitch cam 8 is selectively operated to clear latches for knitting off or to be withdrawn whenever it is desired to accumulate stitches. The said cam 8 is of course withdrawn by the mechanism heretofore described including levers 52 and 55 and the linkage running up to the shaft or spindle 59 and lever and extension 61 and 62. Of course cam 72 is controlled by the lever 78, Fig. 1. At that time the pattern studs or projections 16 in the second row are controlling, that being brought about by movement of levers 52 and 93 to the position of Fig. 5 under the influence of cam 122. Horizontal striping may be controlled at this time by lever 93 and continuing mechanism for governing the stiper drum 101 such control being taken from the fourth row of projections on drum 12. Of course, if it is not desired to stripe the top but to make it plain and to stripe the leg of the stocking only, the pattern may be set up in such a way that the fourth row of projections will be left off in which event the stiper may be maintained inactive.

Now if a pattern is to be knitted in the leg, it may be the same as that of the top or may be changed at will. If it is to be the same as in the top a simple construction might involve the use of long butts 71 on jacks 67 and cam 72 plus the control for front stitch cam 8. However, that would be an extremely simple pattern and the mechanism is, of course, capable of something much more comprehensive so that preferably, when going into the leg of the stocking, cam 72 will be withdrawn and the remaining pattern plungers 128 will, by means of pattern drum control, become effective to act upon removable selective butts 69. Then any tuck

pattern within the scope of the mechanism may be produced.

The determination of needles which are to knit and those which are to tuck will be governed by plungers 128 acting on the jacks and the tuck control drum 12 will still continue to move front stitch cam 8 for completing the tuck pattern, that is, for knitting off at desired courses in which a sufficient number of tuck loops have been accumulated. At such time cam 122 may have allowed levers 52 and 93 to operate on rows three and five on drum 12. That allows control of a tuck in the elastic top or in any other top or portion of a stocking to be changed upon entering the leg or other desired transition point. Now the fifth row of projections will control striping in this second phase of the pattern and, of course, the fifth row may be the same as the fourth row if the stripe in the top and in the leg were to be identical or may be as different as desired, this latter advantage being employed in the knitting of most children's wear in which a horizontal stripe of one type is usually knitted in the top while a second and different horizontal stripe pattern is carried out in the leg and foot. In such wear it is frequently desirable to knit a tuck pattern in the top in addition to such a pattern in the leg. Of course, the control of tucking in the top is not limited to the edge in which elastic is incorporated, but may continue throughout the entire top as for pattern effects.

The control of drum 12, as before stated, is by certain cams on drum 51 acting through lever 48 to move either one or both pawls as shown in Figs. 6 and 7. Cam 138, Fig. 1, is shown with the follower 50 of the lever 48 raised to greatest height. At that time the machine would be in the foot and both pawls would be ratcheting the drum. The bell crank lever having the cam surface 42 would be moved to the position of Fig. 2 at that time. When the toe of that lever drops from cam 138 to a lower cam portion 139, that occurring at the ring toe and toe, the cam surface 42, Fig. 6, will lift pawl 22 from engagement with any of the ratchet teeth. That is for retiming and the drum will move around until pawl 23 arrives at the blank or space 44. Of course, the drum will then stop. After that the machine advances to the top of a stocking and the high cam 140 would encounter the follower 50 again allowing pawl 22 to drop to the ratchet wheel so that the pattern will continue. Of course, the levers 52 and 93 will have been moved to the second and fourth rows of projections as in Fig. 5.

Cam 140 controls throughout the knitting of the top, and in fact, if the top is what is known as a short top, for example, a top for anklets, the cam will be continuous around to and throughout knitting the leg or until the heel is reached. However, if a long top is to be knitted, there is time for retiming the drum preparatory to going into the leg in which event the follower 50 will drop from cam 140 to a low portion of the cam 141 for retiming as in Fig. 6, and thereafter, will be raised on a second high portion 142 for knitting the leg. Then, upon dropping from cam 142, lever 148 is moved to such an extent that both pawls will be withdrawn as in Fig. 7, that is, during knitting the heel; it can be seen that the drum 12 is stopped entirely throughout that function. Of course, at the start of the leg lever 119 will be shifted so that the

third and fifth rows of projections or drum 12 become effective.

The invention has been described relative to one preferred embodiment of the same as exemplified in the figures of drawing, but it is to be understood that many changes may be made without departing from the original inventive concept. The invention is defined in the appended claims.

10 We claim:

1. Pattern means for controlling tuck stitch and horizontal striping functions in a circular independent needle knitting machine including a pattern means periodically movable and having a plurality of rows of pattern conformations thereon, each said row controlling the production of an independent pattern, means for progressively moving said pattern means and conformations and for retiming the same at desired intervals, means for following and receiving patterning impulses from the moving conformations on said pattern means movable to and from different rows of said conformations whereby both patterns may be changed at different points in the knitting.

2. Pattern control means for knitting machines adapted to control a plurality of functions in said machine simultaneously including a pattern drum, several rows of conformations projecting therefrom, levers having pattern followers in alignment with certain spaced rows of conformations and means for moving said levers from a position to be engaged and acted upon by spaced rows of conformations to a second position in which said plurality of levers are acted upon by different rows of conformations.

3. Pattern means for controlling a plurality of functions in a circular independent needle knitting machine including a pattern drum, ratcheting means for moving the same periodically and controlling means for preventing said ratcheting and for causing retiming of the drum, a plurality of rows of pattern conformations variably positioned on said drum, a plurality of levers with followers thereon engageable with rows of conformations and movable transversely of the drum so that a combined pattern may be knitted employing at least two of the rows of pattern conformations and thereafter, a continuing pattern may be controlled employing a different set of pattern conformations as desired.

4. Pattern means for controlling a plurality of functions in a circular independent needle knitting machine including a pattern drum, ratcheting means for moving the drum periodically, means including a cam surface for preventing ratcheting of the drum and for causing retiming of the same, pattern conformations arranged in a plurality of rows on the drum and followers 55 for said rows of conformations mounted on levers 60 movable transversely of the drum, said levers being engageable by a sliding connection with other levers which are in turn connected to control knitting functions on the said machine, means for moving said levers and their followers 65 transversely of the drum including a second drum with a cam thereon and interconnecting means between said drum and cam and the said levers.

5. Pattern means for controlling a plurality of functions in a circular independent needle knitting machine including a pattern drum, rows of conformations on said drum divisible into sets ratcheting means for said drum including a ratcheting wheel and a plurality of movable pawls engageable with teeth on said wheel, cam

means for removing either a single pawl or both pawls from engagement with teeth on the ratchet wheel and further means for controlling the said pawls to engage the ratchet teeth for single or double tooth moves, said last mentioned means being controllable from one row of pattern conformations on the drum, a plurality of levers with followers for said pattern conformations so arranged as to be moved transversely of the drum whereby the said followers engage one set of conformations including a plurality of rows, or a different set including a plurality of rows different from those in the first set, spring means for urging said levers and followers to one position to engage certain of the rows and cam means for moving them in the opposite direction to engage other rows.

6. Pattern means for controlling a plurality of functions in a circular independent needle knitting machine including a pattern drum, ratcheting means for said drum, separately controlled means for stopping the ratcheting of the drum or for varying it so as to retime the same, means for causing the said ratcheting means to impart either single tooth or double tooth movements to the drum, a plurality of levers and followers engageable with rows of spaced pattern conformations on the drum, said rows being divisible into sets, and cam means for varying the position of said levers and followers to change from one set of conformations to a different set, connecting means from said levers to cams which control the knitting functions of the machine including a separable connecting link and a stop mechanism whereby the pattern drum may be ratcheted and movements imparted to the levers and their followers without varying the knitting control at the knitting instrumentalities.

7. In a knitting machine the combination of knitting instrumentalities, cam means for causing said knitting instrumentalities to take yarn and to draw knitted stitches or to take yarn and accumulate loops in the knitting of tuck stitches, and means for changing the sequence of feeding yarns as for horizontal striping including a drum with cams thereon and means for advancing said

drum, and a single pattern control means for determining the knitting of tuck stitches and governing the advance movements of the said drum for changing yarns during horizontal striping.

5. 8. In a knitting machine the combination of knitting instrumentalities, cam means for controlling said knitting instrumentalities, to draw plain knitted loops and tuck stitch loops and 10 yarn feed controlling means adapted to be changed so as to cause the feeding of different yarns as for horizontal striping, means for controlling said last mentioned means including a drum with cams thereon for effecting yarn 15 change movements of the feeding means and means for periodically advancing said drum controlled by a pattern means having a plurality of pattern conformations some of which effect selective positioning of said means for controlling the tuck stitch knitting means and others of which govern the periodic movements of said drum for determining yarn change movements in the horizontal striping.

9. In a knitting machine the combination of knitting instrumentalities, cam means for causing said knitting instrumentalities to take yarn and to draw knitted stitches or to take yarn and accumulate loops in the knitting of tuck stitches, and means for changing the sequence 25 of feeding yarns as for horizontal striping including a drum with cams thereon and means for advancing said drum, and a single pattern control means having several rows of pattern conformations projecting therefrom, pattern 30 following means in alignment with certain spaced rows of formations and means for moving said means from a position to be engaged and acted upon by spaced rows of the conformations to a second position in which said plurality 35 of levers are acted upon by different rows of conformations for determining the knitting of tuck stitches and governing the advance movements of the said drum for changing yarns during horizontal striping.
